[57] CLAIM

The ornamental design for an electrical control box, as shown and described.

DESCRIPTION

FIG. 1 is a front elevational view of an electrical control box showing our new design;
FIG. 2 is the right side elevational view thereof wherein the left side elevational view being the mirror image thereof;
FIG. 3 is a bottom elevational view thereof; and,
FIG. 4 is a perspective view thereof showing the front, bottom, and side view thereof wherein the appearance as seen from the top forms no part of the claimed design.
